UNITED STATES PATENT OFFICE.

ARTHUR E. ARNOLD, OF WEEHAWKEN, NEW JERSEY.

NUT-LOCK.

1,977,248.

Specification of Letters Patent.

Patented Nov. 4, 1913.

Application filed May 11, 1912. Serial No. 696,745.

To all whom it may concern:

Be it known that I, ARTHUR E. ARNOLD, a citizen of the United States, residing at Weehawken, in the county of Hudson and State of New Jersey, have invented new and useful Improvements in Nut-Locks, of which the following is a specification.

This invention relates to improvements in nut locks and, in the present instance, has particular application to a nut lock for holding the nut and pivot bolt of a journal box cover in place.

In carrying out the present invention, it is my purpose to provide a nut lock for journal box covers whereby the nut and pivot bolt of the journal box cover will be securely held in place so that accidental displacement of the nut and pivot bolt, incident to the vibrations of the car, will be eliminated.

It is also my purpose to provide a device of the class described which will embrace the desired features of simplicity, efficiency and durability coupled with cheapness of cost in manufacture and marketing and which will operate effectively for its intended purpose.

With the above and other objects in view, the invention consists in the construction, combination and arrangement of parts hereinafter set forth in and falling within the scope of the claims.

In the drawing, Figure 1 is a front elevation of a journal box and lid embodying my improvement. Fig. 2 is a vertical sectional view upon the line 2—2 of Fig. 1. Fig. 3 is a horizontal sectional view upon the line 3—3 of Fig. 1. Fig. 4 is a vertical sectional view on the line 4—4 of Fig. 3. Fig. 5 is a vertical sectional view on the line 5—5 of Fig. 3.

In the present instance, I have shown my improved nut lock as applied to the cover of a journal box of the M. C. B. type.

It is to be understood that my invention in its useful application is not limited to journal boxes as the same may be employed for other purposes.

Referring now to the drawing in detail, the numeral 1 designates a journal box of the approved M. C. B. type, the same having its top provided with the centrally arranged hinge lug 2 which is extended over its open and inclined outer face.

The numeral 3 designates the lid or cover for the box. This cover comprises a flat-

tended member having its inner face formed with a continuous flange 4 which engages with the sides and lower edge provided by the open face of the box 1. The lid or cover 3 is centrally provided at its upper edge with an integrally formed hood 5, and the numeral 6 designates a flattened spring which is secured to the inner face of the lid or cover as at 7, and which is adapted to exert a tension against the lug 2 of the box to normally sustain the said lid or cover in a closed position upon the box. The lid or cover 3 is also provided upon its upper edge with lugs 8 and 9, the same extending in opposite directions from the sides of the hood to the ends of the lid or cover. Each of these lugs 8 and 9 are provided with centrally arranged rounded bores 10 and 11 respectively, the same adapted to register with the bore of the hinge lug, and the said bores being further adapted to receive the rounded body portion 12 of a hinge pin 13. Communicating with the rounded bores 10 and 11 of the lugs 8 and 9 respectively are angular depressions forming pockets 14 and 15. The pocket 15, which is formed in the lug 9 is of a greater length than the pocket 14 of the lug 8, and adapted to be arranged within the elongated pocket 15 is the angular head 16 of the hinge pin 13.

The numeral 17 designates a helical spring which is adapted to exert a pressure between the shoulder provided by the pocket 15 at its juncture or communication with the bore 11 of the lug 9. The opposite end of the hinge pin 13 may receive the ordinary retaining nut 18, and the said nut as well as the end of the pin may be slotted and provided with a retaining cotter pin 19. In this connection it may be well to state that if desirable the nut 18 may be dispensed with and only the cotter pin employed.

It is to be further understood that the nut is angular or non-circular in cross section and is adapted to be received within the pocket 14 of the lug 8.

In connecting the lid or cover to the journal box, the spring 17 is passed over the rounded portion 12 of the hinge pin until the same contacts with the head 16 of the said pin. The pin is then passed through the alining bores of the lugs of both the box and lid and the head 16 is forced within the pocket 15 of the lug 9 until the end of the pin projects a suitable distance through the bore 14 to receive the retaining element such

as the nut 18 or cotter pin 19. The pressure upon the head 16 of the pin is then released, which causes the spring 17 to exert an outward tension to retain the head 16 within 5 the bore 15 and the locking member for the pin within the bore 14. As the head 16 as well as the locking element for the pin are adapted to snugly engage within the angular pockets, it will be noted that the pin is 10 held against rotation. Furthermore the spring 17 as well as the hinge pin and its locking member being fully concealed they will not be affected by heat resulting from an over-heated journal, or from oxidation.

15 Having thus described the invention, what I claim is:—

1. In combination, two members adapted to be pivotally connected to each other, pivot lugs on said members provided with alining 20 bores, certain of said lugs having non-circular pockets formed therein of various relative depths contiguous the bores, a headed pivot bolt passed through the bores in said lugs and capable of longitudinal movement 25 therein and having the head disposed within the deep pocket and of a contour similar to that of said pocket whereby turning movement of the bolt is prevented, a fastening device secured to one end of said bolt 30 and disposed within the shallow pocket, and shaped to conform to the contour of said pocket whereby rotation of the fastening device within the pocket is prevented, and means surrounding the bolt and disposed 35 within the deep pocket and acting normally to hold the fastening device within the respective pocket.

2. In combination, two members adapted to be pivotally connected to each other, a 40 pivot lug on one of said members and formed with a bore, lugs on the other member spaced apart to embrace the first-mentioned lug and each formed with a bore alining with the bore in the first lug, and 45 a non-circular pocket contiguous said bore and opening into the outer end of the respective lug, one of said pockets being of a depth greater than that of the other, a headed pivot pin passed through the alining bores 50 of said lugs and having the head thereof disposed within the relatively deep pocket,

and of a contour similar to that of said pocket whereby turning movement of the pivot pin is prevented, a securing device on the free end of said pin and adapted to lie 55 within the shallow pocket, and means disposed within the deep pocket and shaped to conform to the contour of said pocket whereby rotation of the securing device within the pocket is prevented and contacting with said pin to hold the securing device thereon in normal position whereby accidental displacement of said fastening device and pin is avoided.

3. In combination, two members adapted 65 to be pivotally connected to each other, a pivot lug on one of said members and formed with a bore, lugs on the other member spaced apart to embrace the first-mentioned lug and each formed with a bore alining 70 with the bore in the first-mentioned lug, and a non-circular pocket contiguous such bore and extending through the outer end of the respective lug, one of said pockets being of a depth greater than that of the other, a headed pivot pin passed through the alining 75 bores of said lugs and having the head thereof disposed in the relatively deep pocket, and of a contour similar to that of said pocket whereby turning movement of said 80 pin is prevented, a securing device on the free end of said pin and adapted to normally lie within the shallow pocket and shaped to conform to the contour of the pocket whereby rotation of said nut within 85 the pocket is prevented, and an expansion spring coiled about said pivot pin and disposed within the relatively deep pocket and having one end bearing upon the adjacent 90 end wall of said pocket and the opposite end abutting the head of said bolt, said spring acting upon the pin to hold the securing device thereon in normal position and within the shallow pocket whereby accidental displacement of said pin and fastening device is eliminated.

In testimony whereof I affix my signature in presence of two witnesses.

ARTHUR E. ARNOLD.
